UNITED STATES PATENT OFFICE

152,038

DESIGN FOR A COAT AND HAT RACK

Anton Stauber, Chicago, Ill.

Application August 6, 1947, Serial No. 140,716

Term of patent 3½ years

(Cl. D17—12)

To all whom it may concern:

Be it known that I, Anton Stauber, a citizen of the United States and a resident of Chicago, in the county of Cook and State of Illinois, have invented a new, original, and ornamental Design for a Coat and Hat Rack, of which the following is a specification, reference being had to the accompanying drawing, forming a part thereof, and in which:

Fig. 1 is a front elevational view of a coat and hat rack, showing my new design;

Fig. 2 is a side elevational view of the same; and

Fig. 3 is a top plan view of the same.

I claim:

The ornamental design for a coat and hat rack, as shown.

ANTON STAUBER.
